CIGAR LIGHTER

Alexander Harris, Newark, N. J., assignor to Art Metal Works, Inc., Newark, N. J., a corporation of New Jersey

Application October 16, 1933, Serial No. 693,705

2 Claims. (Cl. 67—7.1)

The invention relates to a cigar lighter of the pyrophoric type, involving as its main working parts an abradant wheel, snuffer and finger piece, and has special reference to such a cigar lighter wherein the snuffer and abradant wheel are operated by the energy of a spring which is stored therein during movement of the snuffer to closed position, and by transferring energy thereto from another spring which urges the finger piece and snuffer toward their idle positions. In other words, when the finger piece is manually operated, it stores up energy in its spring and the snuffer and abradant wheel are actuated by the first mentioned spring; when the finger piece is released, its spring restores it and the snuffer to idle position, and this latter movement stores up energy in the spring which actuates the snuffer and sparking wheel, which energy is utilized when the finger piece is next manually operated. In so far as I am aware the above principle of alternate transfer of energy from a finger piece spring to a snuffer and abradant wheel actuating spring, has not been heretofore made use of in lighters of the type here involved. Further objects and advantages of the invention will be in part obvious and in part specifically pointed out in the description herein-after contained which, taken in conjunction with the accompanying drawings, discloses a preferred embodiment of the invention; such embodiment, however, is to be regarded merely as illustrative of its principles.

In the drawing—

Fig. 1 is a side view partly cut away of a lighter constructed in accordance with the invention.

Fig. 2 is a similar view showing the parts in light producing position.

The invention is disclosed as applied to a lighter having a fuel receptacle 1 which may be of well known construction, having projecting upwardly therefrom a wick 2, and a piece of sparking metal 3. The main working parts of the lighter, i. e. an abradant wheel 4, snuffer member 5 and finger piece 6 are located over the top of receptacle 1, the finger piece 6 and snuffer 5 being on one side of the wheel and the finger piece 6 on the other side thereof. The U. S. patent to Aronson No. 1,673,727 dated June 12, 1928 may be referred to as illustrating many details of construction of lighters of the above type, which will not be referred to herein since they are well known in the art. The abradant wheel 4 and snuffer 5 are supported in suitable manner over the top of receptacle 1, for example, they

may be pivoted coaxially about a small shaft or transverse spindle 7 located above the top of the receptacle, and the snuffer member 5 may have any suitable pawl and ratchet connection to the abradant wheel 4, a pawl 8 carried by the snuffer being indicated for this purpose, which cooperates with ratchet 9 on the abradant wheel 4.

A spring is provided for moving the snuffer to open position and turning the abradant wheel to produce the spark, the illustrated spring being coiled about the spindle 7 and having one end 10 urging the snuffer upwardly while its other end 11 is fixed to the receptacle 1.

The finger piece 6 is manually depressed through a short path of movement and is urged toward idle position by a spring 12. When the parts are in idle position a lug 13 on the finger piece, by pressing against an adjacent shoulder 14 on the snuffer member 5, presses the snuffer into sealing relation to wick 2, and when the finger piece is manually moved the spring 10, 11, tends to lift the snuffer to open position and (through the pawl 8) turn the sparking wheel 4 to throw sparks against the wick. This opening movement of the snuffer and sparking movement of the abradant wheel may be delayed by a suitable latch member which restrains the snuffer from movement until the finger piece has been moved to any desired extent; for example, in the illustrated form of the invention a latch 15 locks the wheel 4 and snuffer 5 against movement until the finger piece 6 is depressed far enough to move this latch out of engagement with ratchet 9. When the latch 15 is so disengaged the snuffer will fly open until its shoulder 14 comes against a suitable stop, which purpose is served by the lug 13 on the finger piece in the illustrated form of the invention. Thus sparks are projected against the wick and the snuffer stays open so long as the finger piece is held depressed by the user. When manual pressure is released from the finger piece the spring 12 forces the latter to idle position and this spring has sufficient power to push the snuffer (acting through lug 13 and shoulder 14) to closed position against the action of spring 10, 11, thereby storing energy in the latter spring for the next actuation, and holding the snuffer in closed position until finger piece 6 is next manually operated. The latch 15 when used prevents the snuffer and abradant wheel from moving to any substantial extent during the next manual operation of the finger piece, until the finger piece moves this latch out of locking position.

Thus there is no driving connection between the finger piece and snuffer or sparking wheel, during the operation of producing a light, but the spring which drives the last mentioned parts 5 during such operation, is set during the return movement of the finger piece which restores the snuffer, this spring (10, 11), receiving during the movement of the parts to idle position, the energy which is imparted to the finger piece 10 spring 12 during the light producing operation.

While a specific embodiment of the invention has been described it should be understood that changes may be made therein without departing from the invention in its broader aspects, within 15 the scope of the appended claims.

I claim:

1. A lighter of the class described including in combination a receptacle, a wick and snuffer, abradant wheel and finger piece located over the 20 receptacle, said wick and finger piece being located on opposed sides of the abradant wheel, said finger piece being reciprocable and having a spring urging it toward idle position, said snuffer having a part pushed by the finger piece 25 when the latter is moved toward idle position by its spring, to press the snuffer into sealing relation with the wick but said snuffer having no part pushed by the finger piece when the latter is moved from idle position, and a second spring 30 urging the snuffer against the force of the above mentioned spring toward open position and toward engagement with the finger piece, whereby the finger piece stores energy in the snuffer spring when the finger piece moves toward idle position 35 and said energy is utilized when the finger piece

moves from idle position to lighting position, means being provided whereby the abradant wheel is turned to project sparks toward the wick, when the finger piece is moved from idle position.

5

2. A lighter of the class described including in combination a receptacle, a wick and snuffer, abradant wheel and finger piece located over the receptacle, said wick and finger piece being located on opposed sides of the abradant wheel, 10 said finger piece being reciprocable and having a spring urging it toward idle position, said snuffer having a part pushed by the finger piece when the latter is moved toward idle position by its spring, to press the snuffer into sealing 15 relation with the wick but said snuffer having no part pushed by the finger piece when the latter is moved from idle position, and a second spring urging the snuffer toward open position and toward engagement with the finger piece 20 against the force of the above mentioned spring, whereby the finger piece stores energy in the snuffer spring when the finger piece moves toward idle position and said energy is utilized when the finger piece moves from idle position, 25 means being provided whereby the abradant wheel is turned to project sparks toward the wick, when the finger piece is moved from idle position to lighting position, a latch adapted to restrain the snuffer and abradant wheel against 30 movement by said snuffer spring, and means whereby said latch is released during movement of the finger piece from idle position.

ALEXANDER HARRIS. 35
